UNITED STATES PATENT OFFICE.

AUGUST J. KEMPIEN, OF ST. PAUL, MINNESOTA.

BOWLING-ALLEY.

1,137,635.

Specification of Letters Patent. Patented Apr. 27, 1915.

Application filed April 2, 1904. Serial No. 201,209.

To all whom it may concern:

Be it known that I, AUGUST J. KEMPIEN, a citizen of the United States of America, and a resident of St. Paul, in the county of Ramsey and State of Minnesota, have invented 5 certain new and useful Improvements in Bowling-Alleys, of which the following is a specification.

My invention relates to improvements in 10 bowling alleys and has for its primary object the setting of pins accurately and quickly with a minimum amount of hand labor and to produce a device that will accomplish these results which is simple and 15 inexpensive in construction and efficient and effective in operation.

To the above ends my invention consists 20 of a frame mounted to move in a definite path at or near the pit end of the alley, one position which said frame is adapted to assume being substantially horizontal a short distance above the floor of the alley. This frame is formed with spaces through 25 which said pins are guided by the frame into correctly set position on the floor of the alley, said spaces being suitably shaped to permit the frame rising through an arc without disturbing the pins after they have 30 been set. The frame may also be provided with means for swinging it out of position over the pins.

My invention further consists of the features of construction and combination of parts hereinafter more particularly described and claimed.

In the accompanying drawing forming part of this specification; Figure 1 is a plan view of a detail of the pit end of a bowling alley, showing the pin setting frame in lowered position; Fig. 2 is a section taken on the line X—X of Fig. 1; Fig. 3 is a section of a detail showing the pin setting frame in raised position, and Fig. 4 is a longitudinal sectional view of a detail, showing said frame lowered, and Fig. 5 is a section of an alternative construction.

In the drawings A indicates the floor of a bowling alley, B the pit and C—C the return ways for the balls. Secured to the 50 wall 7 of the alley way by means of hinges 6 is a triangular frame D having openings 2 through which the pins 3 may be set. The frame is provided with legs 4 and arms 5 to which the hinges 6 are secured so that 55 the frame may rest upon its legs horizon-

tally above the floor as illustrated in Fig. 2 or may be swung up into superior position as illustrated in Fig. 3. Part of the openings 2 are elongated at 8 away from the hinged end of the frame so that when the 60 frame is swung up into superior position the pins are not disturbed. The openings are spaced apart and clustered in the form of a triangle to spot the pins according to the rules and regulations generally adopted 65 by bowlers. A catch 9 is pivoted at 10 on the wall 7 and is adapted to engage the frame and hold it when raised in superior position. This catch has a spring 11 and a stop 12, said spring serving to hold the 70 catch tightly engaged with the frame but allowing the catch to be disengaged from the frame when desired. The stop 12 serves to limit the movement of the catch caused by the spring 11. 75

Recesses 13 in the wall 7 are formed to receive the frame out of the way after the pins have been set. The frame D may be made out of a thin plate of metal or any other suitable material and it is obvious that 80 it may be of skeleton form when desired. As illustrated in Fig. 5 the frame is counter-balanced by an over head weight 14 which is secured by means of a rope or cable 15 traveling over sheaves 16, to the frame 85 D through the perforated lug 17 on its side. By means of this counter balance the weight of the frame D is relieved so that the frame may be lifted more easily by the operator.

In use the frame D is lowered until it 90 stands by its legs upon the floor of the alley. The pins are then inserted through the openings 2, the frame serving to spot the pins accurately on the floor of the alley. The frame is then raised leaving the pins undisturbed standing upon said floor. The frame may also be used in the following manner with equal effectiveness. The pins are placed upon the floor in approximate position for playing without the use of the 95 frame. The pins are thus only approximately correct in position, it not being possible to always set them in exact position. The frame is then lowered thus adjusting the pins until they assume exactly correct 100 position. The frame is then raised leaving the pins undisturbed and correctly spotted on the floor of the alley. In this manner the pins are always set in the same place. 105

In accordance with the patent statutes I 110

have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

10 Having described my invention, what I claim as new and desire to protect by Letters Patent, is:—

1. Apparatus of the class set forth, comprising, in combination, a bowling alleyway, 15 a swinging frame pivoted adjoining the alleyway and having passages through which the pins are spotted and means for supporting it above the floor of the alleyway when in lowered position, said passages 20 being elongated to permit said frame swinging up without disarranging the pin.

2. Apparatus of the class set forth, comprising, in combination, a swinging frame pivoted to swing from over the alleyway and having openings for spotting the pins elongated to permit the frame being swung upwardly without disarranging said pins, means for holding said frame in superior 25 position and means for supporting said frame above the floor of the alleyway when 30 in lowered position.

3. A bowling alley having, in combination with its floor A near the pit end thereof, a frame D having openings 2 and elongations 35 8 to said openings, means for supporting said frame in horizontal position above said floor, a hinged connection between the frame and a side of the alley for swinging the frame out of operative position, and a catch 40 9 on the side of the alley for holding the frame in superior position.

4. Apparatus of the class set forth, comprising, in combination, an alley proper, a swinging frame pivoted clear of said alley 45 proper for spotting the pins, said frame having openings in which the pins are received elongated to permit the frame swinging up without disarranging the pins and means for supporting said frame above the 50 floor of the alley proper when in lowered position.

5. Apparatus of the class set forth, comprising, in combination, an alley proper, and a swinging frame pivoted clear of said alley proper for spotting the pins, said frame having openings to receive the pins elongated to permit the frame swinging clear

of the alley proper without disturbing said pins.

6. A bowling alley, comprising, in combination, an alley floor having a wall at one side, a swinging frame pivoted clear of said alley floor for spotting pins, said frame being adapted to swing up from the alley floor and said wall being formed with a recess into which said frame is received when the latter is in its uppermost position, and said frame having openings in which the pins are received and through which they are adapted to be positioned on the alley floor.

7. Apparatus of the class set forth, comprising, in combination, an alley proper, and a swinging frame pivoted clear of said alley proper counterbalanced to assist in raising it, said frame having openings through which the pins are passed to spot them on the alley proper and elongated to permit said frame swinging clear of the alley proper without disturbing said pins.

8. In a bowling alleyway, a pin spotter pivoted to swing from directly over the alleyway, said spotter consisting of a frame having a plurality of pin receiving openings, the margin of each of said openings substantially coinciding with the side wall of a pin to position it on a spot, said frame having a cut-out portion to one side of and communicating with the opening in the frame to permit the same being moved freely to one side of the pin.

9. In a bowling alleyway, a pin spotter frame having an opening, the margin of said opening being adapted to coincide with the side wall of a pin to spot said pin, said frame having a cut-out portion to one side of and communicating with the opening in the frame to permit the same being moved freely to one side of the pin.

10. In a bowling alleyway, a pin spotter frame having an opening, the margin of said opening being adapted to coincide with the side wall of a pin to spot said pin, said margin being extended in one direction to permit said frame being moved to one side of said pin.

In testimony whereof I have signed my name to this specification in the presence of two subscribing witnesses.

AUGUST J. KEMPIEN.
